UNITED STATES PATENT OFFICE.

WILLIAM M. PIATT, OF MAC-O-CHEE, OHIO, ASSIGNOR OF ONE-THIRD TO
BENJAMIN P. RUNKLE, OF SAME PLACE.

GRAIN-BINDER.

SPECIFICATION forming part of Letters Patent No. 377,731, dated February 7, 1883.

Application filed November 15, 1886. Serial No. 218,945. (No model.)

To all whom it may concern:

Be it known that I, WILLIAM M. PIATT, a citizen of the United States, residing at Mac-o-chee, in the county of Logan and State of Ohio, have invented Improvements in Grain-Binders, of which the following is a specification.

In order that my invention may be fully understood, I will proceed to describe it with reference to the accompanying drawings, in which—

Figure I is a plan view of the platform portion of the machine. Fig. II is a perspective view of the means by which the height of cut is regulated on the stubble side of the machine. Fig. III is a transverse section of a channel steel bar employed in the construction of the platform. Fig. IV is a side elevation of the grain side of the machine, showing the means by which the height of cut is regulated on the grain side. Fig. V is an elevation of the machine, looking from the stubble side of the machine. Fig. VI is a rear elevation of the binder portion of the machine. Fig. VII is a side elevation of a cam-track arm and compressor. Fig. VII^a is a side elevation of a retaining-finger and its lifting-cam. Fig. VII^b is a side elevation of a combined compressor and retainer. Fig. VII^c is a plan view of the finger portion thereof. Fig. VIII is a vertical section of the machine inside of the driving-wheel, looking from the stubble side. Fig. IX is a side elevation of the gear for operating the knotter and compressor. Fig. X is a front elevation of the binder portion of the machine. Fig. XI is a perspective view of the trip-arm. Fig. XII is a view of a portion of the reel, showing a bat provided with a sliding knuckle. Fig. XIII is a top view of the reel-supporting arms and adjacent parts.

My main frame is constructed in substantial form of channel steel bars, for the reason that I have found this kind of bar preferable to angle steel bars or gas-pipe for this purpose. A transverse section of the bar is shown in Fig. III. The frame is formed of a bar starting with a straight portion, 1, parallel with the cutter-bar 21, forward straight portion, 2, curved portion 3, straight portion 4, curved portion 5, rearward straight portion 6, extending as far rearward as a line drawn lengthwise through the middle portion of the main

platform 32, curved portion 7, straight portion 8, curved portion 9, forward straight portion 10, curved portion 11, straight portion 12, secured to the portion 4, curved portion 13, rearward straight portion 14, curved portion 15, straight portion 16, parallel with the cutter-bar, curved portion 17, forward straight portion 18, curved portion 19, and straight portion 20, parallel with the cutter-bar, extending under the portions 14 and 10 to the center portion of the latter, to which it is secured. This frame is re-enforced or strengthened by a U-shaped bar, 22, bolted to the straight portions 10 and 14 and to the end of the portion 20 within the latter. The frame is further re-enforced and strengthened by a bar, 23, extending from the curved portion 5 to the end of the binding-table, conforming to the shape of the frame and bolted thereto, with the exception of the U-shaped portion 25, which is similar to the other U-shaped bar on the opposite side of the end of the portion 20 of the bar. The grain end of the platform-frame is strengthened by a bar, 23^a, extending from the curved portion 17 to the end of the divider. This form of main frame provides a main frame having an opening, 26, for the driving-wheel 27, a deep recess, 28, for the sheaf to fall through, a binding-table frame, 29, having forward extension, 30, connected by a neck-frame, 31, in front of the recess to the frame surrounding the driving-wheel and an ample platform-frame, 32, for the grain to fall on.

33 is a yoke-frame having arms 33^a and 33^b extending from the rear of the wheel-frame upward and then downward, hinged by short shafts 34 35 to the forward ends of bars 6 10 within the opening 26, and to the top of this frame 33 is journaled by axle 36 the driving-wheel 27. To the rear of the frame 33 is secured a rack-segment, 37, engaged by a worm-shaft, 38, to provide means by which the main frame can be raised or lowered on the driving-wheel for regulating the height of cut at that side of the machine. Secured in line with the cutter-bar on the outside of the divider is the grain-wheel 39. To the spindle 40 of the grain-wheel is hinged a rack-segment, 41, pivoted to a stud, 42, and having an arm, 43, forming a lever by which the main frame can be raised

and lowered on the grain-wheel for regulating the height of cut. Strapped to the side of the divider is a spring-bolt, 44, engaging the rack-segment. The bolt is retracted by a hinged 5 arm, 45, connected to a swinging bar, 46, having a rod, 47, by which it is coupled to a short lever, 48, hinged to the arm of the rack-segment. The platform-frame is braced transversely by a bar, 49, extending from the curved 10 portion 3 to the portion 16 beneath the frame.

50 is the standard of the binder, mounted on a sliding section, 51, of the binding-table 52, to permit the adjustment of the binder for short or long grain. The binder is adjusted 15 by means of a rock-shaft, 53, having an arm, 54, connected to a link, 55, on the standard, and an arm, 56, connected by a rod, 57, with a lever, 58, hinged to a stud, 59, on the main frame, which also supports a rack-segment, 60, 20 engaged by a spring-latch, 61, for holding the lever to its adjusted position and the standard stationary. The standard is formed with the usual arm, 62, and head 63.

Journalized in the arm 62 is the needle-shaft 25 64, which operates the needle-bar 65 in the head 63.

66 is the packer-shaft, supported on the short standard 67 at the standard end of the binding-table, and journalized in a bracket, 68, 30 secured to the head 63 at the rear end of the table.

69 is the inner ejector-shaft, journalized in the standard and in a bracket, 72, at the stubble side of the head.

35 71 is the outer ejector-shaft, journalized in the brackets 70 and 72. Extending from the shaft 66 to the shaft 69, and mounted thereon beneath the arm 62 and also outside the head, are the cam-track arms 73, provided with 40 cam-tracks 74, sprocket-wheels 75, endless chains 76, and forwarding-fingers 77. The cam-track arms outside the head have a swinging track, 78, suspended from the cam-tracks by links 79, and from a lifting-rod, 80, supported by a lever, 81, having slot 82 at its outer end receiving a pin, 83, on the head 63, and at its inner end provided with a wrist-pin, 84, working in a groove, 85, in a cam, 86, secured to the needle-shaft and constructed in

50 the back of the needle-driving crank. Extending from the inner ejector-shaft to the outer ejector-shaft are the cam-tracks 87, provided with sprocket-wheels 88, endless chain 89, and discharging-arms 90. Hinged to the 55 inner ejector-shaft, between the cam-tracks 87 and the cam-track arms 73, are the retaining-fingers 91, having pins 92, and supported by cams 93 on the outer ejector-shaft, having grooves 94, in which the pins engage. Parallel with the needle-shaft, and mounted in brackets 95, secured to the standard and head, is another shaft, 96, having a crank, 97, on which is suspended a link, 98, supporting a spring-bar, 99, hinged to the inner ejector-shaft by

60 a coil, 100, at its middle portion, and extending downward to provide a compressor for the bundle formed thereunder.

In Figs. VII^b and VII^c I show a modification in the construction of the retaining-fingers and compressor, in which the retaining-fingers 70 and compressor are combined.

99^a represents compressor and retaining-fingers hinged by coils 100^a to pin 92^c, working in the grooves 94 of cams 93, secured to the shaft 71. The pin 92^a is supported in the ends of 75 arms or bars 91^a, mounted upon the shaft 69. The inner ends, 100^c, of the fingers 99^c are secured to a cylinder, 100^b, which is supported by a piston-rod, 98^a, hinged to the crank 97 of the compressor-shaft 96. Within the cylinder, between its head 100^c and the piston 100^b, I place a spring-coil, 100^a, for holding the fingers in normal position until operated. Supported in bearings 101 on the standard and head and extending over the arm 62 is a rock-shaft, 102, having an arm, 103, alongside of the head, on which is supported a trip-arm or trigger, 104, by means of a rod, 105, the trip-arm or trigger being hinged to a stud, 106, on the lower portion of the head. 107 are 90 hangers on the sliding portion 51 of the table, in which is mounted the knotter-shaft 108, operating a knotting mechanism, 109. 110 is the needle-slot.

On the top of the standard are supports 95 111, having bearings for a shaft, 112, on which arms 113 are hinged. In the inner ends of said arms is journalized the reel-shaft 114, mounted on a suitable adjustable support. (Not shown.) A sleeve, 115, secured to the 100 arms, is formed with a stud, 116, working in a slot, 117, in an arm, 118, on which it is guided.

119 and 120 are sprocket-wheels on the shaft 112 and reel-shaft 114, respectively, connected 105 by an endless chain, 121. The reel-shaft has arms 122, to which are secured the bats 123 by knuckles 124 and straps 125 at their outer ends, and by hinges 126 at their inner ends. The cutter-bar 21 is operated by a pitman, 127, connected with the wrist-pin 128 on a crank, 129, secured to a shaft, 130, journalized in the neck portion 31 of the frame.

131 is the inner roller of the endless apron 131^a, having a shaft, 132, extending across the 115 main frame lengthwise of the table.

The various parts are operated by the following means: On the inner side of the driving-wheel is an interior gear, 133, meshing with a gear-wheel, 134, on the shaft 35, having at its inner end a bevel gear-wheel, 135, meshing with another bevel gear-wheel, 136, on a shaft, 137, having a gear-wheel, 138, meshing with a gear-wheel, 139, on the crank-shaft 130, and provided with a sprocket-wheel, 140, driving an endless chain, 141, passing over a sprocket-wheel, 142, on a shaft, 143, under a pulley, 144, over a sprocket-wheel, 145, on the packer-shaft, under a sprocket-wheel, 146, on the apron-shaft, and 130 over the sprocket-wheel 147, which is mounted on a shaft, 148, and back to the sprocket-wheel 140.

At the inner end of the shaft 148 is secured

the bevel gear-wheel 149, meshing with a bevel gear-wheel, 150, on the shaft 112. Adjustable on the shaft 143, and keyed thereto by a spline, 151, is a bevel-pinion, 152, meshing with the 5 bevel gear-wheel 153 on the lower end of a vertical shaft, 154, having bearings within the standard 50, and provided with a bevel gear-wheel, 155, at its upper end, meshing with a bevel gear-wheel, 156, turning loosely on the 10 needle-shaft 64, and formed with a cross-bar, 157, having pins 158 on the outside of the standard.

On the front end or outer end of the needle-shaft and keyed thereto is a mutilated gear-wheel 159, having a segment-gear, 160, covering a portion of its periphery, and provided on its inner side with a trip-hook or latch, 161, pivoted to its rim, pressed inward to engage a pin, 158, on the cross-bar by means of 15 a spring, 162, bearing against its heel and held from engagement by means of an arm, 163, on the trip-shaft, bearing on the projection 173 on the hook. 164 is a gear-wheel on the compressor-shaft, and 165 is a gear-wheel 20 on the inner ejector-shaft engaged by the segment-gear of the mutilated gear-wheel 159. These gear-wheels 164 and 165 are provided with delay-shoes 166 and 167, respectively, bearing on the side of the toothless or plain 25 portion of the mutilated gear-wheel. Parallel with the vertical shaft 154 is another shaft, 168.

Keyed to the compressor-shaft 96 is a bevel gear-wheel, 169, meshing with a bevel gear-wheel, 170, on the upper end of the vertical shaft 168, having a bevel-pinion, 171, at its lower end meshing with a bevel-pinion, 172, on the knotter-shaft 108. The wheels and shafts move in the directions indicated by the 30 arrows.

The operation of the machine is as follows: The grain being presented to the cutters by the adjustable reel, the falling grain is received upon the main apron and fed to the packers 45 or fingers 77, which transfer it to a position under the trip or trigger 104, compressor 99, and retainers 91, against the twine between the gripper (not shown) and the needle, and in rear of discharging-fingers 90. As the grain 50 accumulates under the trip or trigger, it gradually raises it until the arm 163 is disengaged from the projection 173 on the hook 161 of the mutilated gear-wheel, permitting the hook to drop in advance of a pin, 158, on the cross-bar 55 157 of the loose motive wheel 156. The pin, coming in contact with the hook, pulls on the mutilated gear-wheel 159, causing it to turn, together with the needle-shaft, simultaneously 60 depressing the needle-bar to deliver the twine to the knotting mechanism and lifting the track 78 of the packers to stop the feeding of the latter. The gear 160 next revolves the wheel 164, which simultaneously operates the knotting mechanism and compressor, the latter 65 tightening or compacting the bundle for permitting the knotter to take the twine (sufficient for knotting) from around the bundle,

the two ends of the loop being held by the gripper and needle until the knot is secured, and then the twine is severed. The continued 70 rotation of the mutilated gear-wheel brings its gear into mesh with the gear-wheel 165, which simultaneously causes the cam 93 to operate to lift the retaining-fingers 91 out of the way of the bundle, and advances the discharging-fingers 90 to discharge the sheaf. After the 75 sheaf is discharged the various parts assume their normal positions by the time the wheel 159 reaches the position in which the arm 163 arrests its movement by falling in the path of 80 the projection on the hook, the rotation of the gear-wheels 164 and 165 being arrested by the delay-shoes bearing on the plain portion of the rim of the mutilated gear-wheel.

Having thus described my invention, the following is what I claim as new therein and desire to secure by Letters Patent:

1. A main frame for a grain-binder, consisting of the bar forming a platform-frame, 32, a binding-table frame, 29, having forward extension, 30, a drive-wheel frame extending as far rearward as a line drawn lengthwise through the middle of the platform-frame, and a neck-frame, 31, connecting the forward extension to the front portion of the driving-wheel frame, forming the recess 28, all substantially as shown and described. 85

2. A main frame for a grain-binder, consisting of the bar formed with platform-frame, binding-table frame, forward extension to the 100 table-frame, neck-frame, driving-wheel frame, and U-shaped brace 22 within the neck-frame, substantially as shown and described.

3. A main frame for a grain-binder, consisting of the bar formed with platform-frame, 105 binding-table frame, forward extension to the table-frame, neck-frame, driving-wheel frame, and the brace 23, having U-shaped portion 25, substantially as shown and described.

4. The combination of the brace-bar 49 with 110 the main frame, consisting of a bar formed with platform-frame, binding-table frame, forward extension to the table-frame, neck-frame, and driving-wheel frame, the brace extending from the curved portion 3 to the 115 straight portion 16 beneath the parallel portions 1 and 20, substantially as shown and described.

5. The combination, with the packer-shaft, the binding-table, and the standard having an arm and head, of the needle-shaft provided with a cam, 86, having a groove, 87, the arms 73, having cam-tracks 74, sprocket-wheels 75, journaled in the arms, endless chain 76, having fingers 77, for advancing the grain beneath the 120 arms, the links 79, secured between the arms, the swinging track 78, suspended from the links, the lever 81, secured to the head, having a wrist-pin, 84, working in the groove of the cam, and a rod, 80, connecting the lever with 125 the swinging track, substantially as described.

6. The combination, with the standard having an arm and head, the binding-table, the inner ejector-shaft, 69, the outer ejector-shaft,

71, cam-tracks 87, extending from shaft to shaft, the sprocket-wheels 88, and endless chain 89, having discharging-arms 90, of the retaining-finger 91, hinged to the inner ejector-shaft, and devices by which the finger is suspended on the outer ejector-shaft and raised and lowered by the latter, substantially as described.

7. The combination, with the inner and outer ejector-shafts, of the retaining-finger 91, hinged to the inner ejector-shaft, having a pin, 92, and the cam 93 on the outer ejector-shaft, having a groove, 94, in which the pin travels, substantially as described.

15 8. The combination, with the inner and outer ejector-shafts, of the retaining-finger 91, hinged to the inner ejector-shaft, and means on the outer ejector-shaft for raising and lowering the finger, substantially as described.

20 9. The combination, with the ejectors and the inner and outer ejector-shafts, of the compressor formed of a spring-bar, 99, mounted on the inner ejector-shaft, and mechanism, substantially as shown and described, by which 25 the compressor is raised and lowered.

10. The combination, with the standard formed with an arm and head, the inner ejector-shaft, 69, and a binding-table, of the shaft 96, mounted on the arm, having a crank, 30 97, link 98, suspended on the crank, and the spring-bar hinged to the inner ejector-shaft and supported on the link, substantially as described.

11. The combination of the rock-shaft 102, 35 having an arm, 163, trigger or trip-arm 104, connections between the trigger or trip-arm and rock-shaft, mutilated gear-wheel 159, needle-shaft 64, loose wheel 156, having cross-bar 157, provided with pin 158, and the spring-hook 161, secured to the mutilated gear-wheel, 40 having a projection, 173, substantially as described.

12. The combination of the trigger or trip-arm, the arm 163, devices connecting the trigger or trip-arm to the arm, the mutilated gear-wheel 159, having spring-latch 161, provided with projection 173, needle-shaft 64, loose wheel 156, having cross-bar 157, provided with pins 158, the compressor, compressor-shaft 96, 45 connections between the compressor and its shaft, and gear-wheel 164, substantially as described.

13. The combination of the trigger or trip-arm, the arm 163, devices connecting the trigger or trip arm to the arm, the mutilated gear-wheel 159, having spring-latch 161, provided with projection 173, the needle-shaft 64, loose wheel 156, having cross-bar 157, provided with pins 158, the inner ejector-shaft, 69, having 50 gear-wheel 165, the outer ejector-shaft, 71, sprocket-wheels 88, endless chain 89, and discharging-arms 90, substantially as described.

14. The combination of the needle-shaft 64, loose wheel 156, having cross-bar 157, provided with pins 158, mutilated gear-wheel 159, 55 having spring-latch 161, means for operating

the latch, compressor-shaft 96, bevel-wheel 169, gear-wheel 164, vertical shaft 168, bevel-wheels 170 and 171, knotter-shaft 108, bevel-wheel 172, and knotting mechanism, substantially as described.

15. The combination of the needle shaft 64, loose wheel 156, having cross-bar 157, provided with pins 158, mutilated gear-wheel 159, having a segment-gear, 160, the spring-latch 161, pivoted to the mutilated gear-wheel, 75 means for operating the latch, compressor-shaft 96, having gear-wheel 164, inner ejector-shaft having gear-wheel 165, and the outer ejector-shaft, substantially as described.

16. The combination of the needle-shaft 64, loose wheel 156, having cross-bar 157, provided with pins 158, mutilated gear-wheel 159, having a segment-gear, 160, the spring-latch 161, pivoted to the mutilated gear-wheel, 85 means for operating the latch, needle-bar 65, cam 86, having groove 85, lifting track 78, and means connecting the cam and lifting-track, substantially as described.

17. The combination of the binding-table, a support over the binding-table, the packer-shaft, the arms 73, having cam-tracks 74, sprocket-wheels 75, journaled in the arms, endless chain 76, having fingers 77, for advancing the grain beneath the arms, the swing-track between the sprocket-wheels, the inner ejector-shaft, the outer ejector-shaft, cam-tracks extending across the ejector-shafts, sprocket-wheels on the ejector-shafts, endless chain having discharging-arms, and retaining-arm hinged to the inner ejector-shaft and supported on the outer ejector-shaft, substantially as described.

18. The combination of the binding-table, a support over the binding-table, the packer-shaft, the arms 73, having cam-tracks 74, sprocket-wheels 75, journaled in the arms, endless chain 76, having fingers 77, for advancing the grain beneath the arms, the shiftable-track portion, the inner and outer ejector-shafts, cam-tracks extending across the ejector-shafts, sprocket-wheels on the ejector-shafts, endless chain having discharging-arms, retaining-arms hinged to the inner ejector-shaft and supported on the outer ejector-shaft, and the compressor hinged to the front ejector-shaft, substantially as described.

19. The combination of the binding-table, a support over the binding-table, the packers for transferring the grain on the table beneath, 120 the inner and outer ejector-shafts, cam-tracks extending across the ejector-shafts, sprocket-wheels on the ejector-shafts, endless chain having discharging-arms, the retaining-arms hinged to the inner ejector-shaft and supported 125 on the outer ejector-shaft, the compressor hinged to the inner ejector-shaft, and the trigger or trip-arm, substantially as described.

WILLIAM M. PIATT.
